[57] CLAIM

The ornamental design for a case for holding a compact disc player and compact discs with interconnected belt, as shown and described.

DESCRIPTION

FIG. 1 is a front perspective view of a case for holding a compact disc player and compact discs with interconnected belt, showing my new design with the case in a partially open position, with environment;

FIG. 2 is a front elevation view of the invention illustrated in FIG. 1;

FIG. 3 is a top plan view of the invention illustrated in FIG. 1;

FIG. 4 is a rear elevation view of the invention illustrated in FIG. 1;

FIG. 5 is a bottom plan view of the invention illustrated in FIG. 1;

FIG. 6 is a left elevation view of the invention illustrated in FIG. 1; and,

FIG. 7 is a right elevation view of the invention illustrated in FIG. 1.

The broken line showing the environment in the drawings is for illustrative purposes only and forms no part of the claimed design.
